UNITED STATES PATENT OFFICE.

CHARLES D. WARNER, OF ANSONIA, CONNECTICUT.

ELECTRIC GAGE.

SPECIFICATION forming part of Letters Patent No. 309,114, dated December 9, 1884.

Application filed March 10, 1884. (No model.)

To all whom it may concern:

Be it known that I, CHARLES D. WARNER, a citizen of the United States, and a resident of Ansonia, in the county of New Haven and 5 State of Connecticut, have invented certain new and useful Improvements in Electric Gages, of which the following is a specification.

My invention belongs to that class of devices by means of which the strength of current and the changes thereof in an electric conductor are indicated upon a properly-divided scale through the force exerted by said current in the coils of an electro-magnet upon 15 an armature placed in the field of force of said magnet.

The object of my invention is to afford a simple and effective gage which shall indicate at all times the strength of current in 20 circuits where work is done by means of one or more electro-magnets—such as clock or telegraphic circuits—and which shall show at once the changes that may take place in the current strength in the circuit which includes the 25 device.

My invention consists, generally, of an electro-magnet designed to be placed in series with the working electro-magnets of the circuit, having an armature held normally in a 30 position in which it is but partially within the field of force of the magnet. The armature is connected by suitable mechanism to a pointer or hand placed in front of a divided scale, and the same is so adjusted that when no current 35 is passing the index stands at zero, being held in that position by a spring or other extraneous force. The passage of a current tends to bring the armature into a position normal to the lines of force exerted by the magnet, 40 which causes the index-hand to pass over the scale, indicating by its position the balance between the magnetic force and that tending to keep the hand at zero. In my invention the magnet has curved pole-pieces, the armature is a segment of a circle, and suspended 45 by an arm or arms at the center of the segment, so that when the segment-armature swings upon its center it passes close to the pole-pieces, and therefore into the field of force. The armature is held at one side by a suitable spring, and the effect of the attraction of the poles upon the armature is to draw 50

the armature into a central position opposite the said poles. Means for altering the distance between the poles and armature are 55 provided, so that the same scale may serve for circuits operated by currents of greater or less strength. Any change in the strength of current will be at once indicated by the change of position of the index, which follows the 60 change of position of the armature with reference to the poles of the magnet.

The invention is especially adapted to clock-circuits, where a series of electro-magnets are required to do regular work, where the strength 65 of current is required to be as nearly constant as possible, and where it is desired to know at frequent intervals whether any change in the condition of the battery or the external circuit has taken place.

My invention is illustrated in the accompanying drawings, in which Figure 1 is a front elevation of the instrument, showing case, dial, and index. Fig. 2 is a front elevation with the case and dial removed. Fig. 3 is a 75 rear elevation with the back portion of the case partly removed, and Fig. 4 is a vertical transverse section of the instrument.

In the drawings, A represents the case of the instrument; B, the dial; C, the index-hand. 80 The dial is represented as graduated from 0 to 60; but any arbitrary or other method of division may be adopted. The index-hand is mounted upon a central arbor, c, and is balanced by the extension and weight c². The 85 instrument has front and back frames, D and D', fastened together by the rods d' d² d³ d⁴, between which the electro-magnet E is placed. Curved pole-pieces E' E' are attached to the cores. Above the magnet is suspended the 90 armature F, formed into the segment of a circle, having the arms f f', and turning at the center of the circle upon the arbor f', which has bearings in the front and back frame plates of the instrument. The armature is balanced 95 by the extension f² and weight f³. The curved piece D² is a portion of the front frame of the instrument, and attached to this is the piece D³, projecting in front of the piece D². The pieces D² and D³ are pierced for the bearings 100 of the arbor c, which carries the index. The spiral spring s is attached at one end to the arbor c, and at the other end to the back side of the piece D³. Back of the spring s, and

fixed on the arbor c , is a small cog-wheel or pinion, c' . This pinion c' , it will be seen, is in front of the front plate, and it engages with the gear-cut segment g , having the arms $g' g'$, and which turns upon the same pivot, f' , as the armature. The segment g and the armature are equal segments and correspond in position to each other. The spring s is so adjusted as to have a tendency to turn the arbor c , and therefore the pinion c' , and thus to hold the segment g and the armature F to one side. The pin e' acts as a stop to the segment g when it and the armature have reached an extreme position at one side of the magnet E . In this position the cog-wheel c' is in engagement with the cogs at the end of the segment g , and the end of the armature is slightly past the central point of the coils. The relative positions of the magnet and armature and of the armature and segment g may be varied without departing from the principle of the invention. When the armature and segment are in their extreme position at one side of the magnet, the index is set at zero. The terminal wires of the electro-magnet E are connected with the binding-posts $P P$ on the outside of the case, and the instrument may thus be connected in circuit. It is evident that when an electric current is passing through the coils of the magnet the armature is drawn away from its position at one side of the coils and will move toward a central position—that is, a position in which the middle of the armature is opposite the point m , centrally between the two coils—and if the instrument is so adjusted that the armature will reach the central position only when under the influence of the strongest current which may be used upon the line, then all strengths of current from such greatest strength to zero can be indicated by the intermediate positions of the armature and the index. The electro-magnet is movable between the front and back frame pieces of the instrument.

In Fig. 3 is shown the means for holding and moving the coils, so as to vary the distance between the pole-pieces and the armature. The back plate of the frame is shown at D' . The piece H is bent at right angles, one end being attached to the yoke of the electro-magnet, and the other end, as shown, extends parallel and close to the piece D' of the frame-plate. The piece H has elongated holes $h h$, through which pass the screws $k k$. These screws pass through the washers $l l$, then through the piece H and into the frame-piece D . The magnet, therefore, can be moved up or down by means of the piece H , guided and held in position by the screws $k k$. The upper end of the piece H is formed into the narrow piece or extension h' , and this rests against the edge of the cam M . The cam is fixed upon the arbor m' , which has bearings in the frame-plate D' and in the cross-piece D^t , which is attached to the plate D' at each end by screws $d^s d^b$.

N N are two springs attached to the plate D^s by the screws $d^s d^b$, and tend to push upward the piece H , which carries the magnets, and it tends, therefore, to hold the pole-pieces close to the armature. The piece h' , meeting the edge of the cam M , limits the movement of the magnet toward the coils. It is evident, now, that by turning the arbor m' , and therefore the cam M , the piece H will be moved, and thereby the magnet. Thus, if the parts are in the position shown in Fig. 3, the end of the piece h' rests against the edge of the cam at a point something more than a quadrant from the point m^2 , which is nearest the center. When the cam is in position so that the end of the extension h' rests against the point m^2 , it is evident that the pole-piece will be nearest the armature. When the cam is turned so that the end of extension h' rests against the point m^3 at the end of the largest diameter of the cam, then the magnet is held at its farthest distance from the armature. It is easy, therefore, to adjust the distance of the pole-pieces and armature for any strength of current, while the tension of the spring s , which acts upon the armature, may remain constant.

The distance of the pole-pieces from the armature is indicated by the index I , which is fixed upon the arbor m' , and which passes over a scale, T , upon the outside of the back plate of the instrument, the index standing at 1 when the pole-pieces are nearest the armature—that is, when the end of h' rests against the point m^2 —and it stands nearly at the same mark when the cam is turned so that the end of h' rests against the point m^3 , the index having passed around the scale, and the pole-pieces are at their farthest distance from the armature.

In practice the distance of the poles and armature is adjusted for the strength of current in the circuit in which the instrument is to be placed by turning the index and cam until, when the circuit-connections are made, the index on the front dial stands at a convenient point—say 30—thus giving a sufficient range on each side for indicating any changes that may take place. Anything which then affects the efficiency of the current for the work it is doing may be immediately sought out and remedied.

I claim as my invention—

1. The combination, substantially as hereinbefore set forth, of an electro-magnet, curved pole-pieces to said magnet, an armature formed into the segment of a circle, said armature being suspended at its center of curvature, a counter-balance or equivalent device for holding said armature away from the center of the field of force of said magnet, an index or pointer, and means, consisting, substantially, of a rack and pinion, for moving said index correlative with the movements of said armature toward and away from the center of the field of force of said magnet.

2. The combination, substantially as hereinbefore set forth, of an electro-magnet, its ar-

mature, a counter-balance or equivalent, means for holding said armature away from the position where said magnet will exert upon said armature its greatest force, an index or pointer, 5 and mechanical connections between said index and the armature for moving said index correlatively with the movements of said armature to or away from said position of greatest magnetic force, an adjustable frame carrying the electro-magnet, whereby the distance between said armature and the poles of said magnet may be varied.

3. The combination, substantially as hereinbefore set forth, of an electro-magnet, curved 15 pole-pieces to said magnet, an armature forming the segment of a circle and suspended at the center of curvature of said segment, an index or pointer mechanically connected with the axis of said armature, whereby said index 20 is adapted to move correlatively with said armature into and away from a central position with reference to said pole-pieces, and a divided scale before which said index moves.

4. The combination, substantially as hereinbefore set forth, of an electro-magnet, its armature, a spring or equivalent device for holding said armature away from a central position with reference to the lines of force of said 25 magnet, an index or pointer, and mechanical

connections between said index and armature 30 for moving said index correlatively with the movements of said armature, a divided scale for indicating the position of said armature in the field of force of said magnet, an adjustable frame carrying the electro-magnet, whereby 35 the same may be moved to and from the path of said armature, and an index and divided scale for indicating the distance between said armature and the poles of said magnet.

5. The combination, substantially as hereinbefore set forth, of the magnet E, the curved armature F, the segment g, the pinion c', and the index C.

6. The combination, substantially as hereinbefore set forth, of the magnet E, the pole-pieces E', the curved armature F, the segment g, the pinion c', the spring s, the index C, the dial B, the piece H, to which said magnet is attached, the cam M, the springs N, the index I, and scale T.

In testimony whereof I have hereunto subscribed my name this 6th day of March, A. D. 1884.

CHARLES D. WARNER.
